[57] **CLAIM**

The ornamental design for yoked chop sticks, as shown
and described.

DESCRIPTION

FIG. 1 is a front elevational view of yoked chop sticks
showing my new design; the rear elevational view being
substantially a mirror image thereof;

FIG. 2 is a top plan view thereof;

FIG. 3 is a left side elevational view thereof;

FIG. 4 is a right side elevational view thereof; and

FIG. 5 is a bottom plan view thereof.

FIG. 2.

FIG. 3.

FIG. 1.

FIG. 4.

FIG. 5.
